UNITED STATES PATENT OFFICE.

JOHN A. SHEPHARD, OF NEW YORK, N. Y.

DESIGN FOR A BOTTLE-STOPPER.

SPECIFICATION forming part of Design No. 23,412, dated July 3, 1894.

Application filed May 5, 1894. Serial No. 510,223. Term of patent 14 years.

To all whom it may concern:

Be it known that I, JOHN A. SHEPHARD, a citizen of the United States, residing at New York city, in the county of New York and State of New York, have invented and produced a certain new and original Design for Bottle-Stoppers; and I do hereby declare the following to be a full, clear, and exact description of the invention, such as will enable others skilled in the art to which it appertains to make and use the same.

The design is illustrated in the accompanying drawing, which is an exterior view in elevation.

15 The leading parts of my design when assembled, resemble the form of a thistle, in which A is the stem, B the body or calyx, and C, the corona or flower.

The body B is circular in form and is formed with diamond shaped protuberances, c, to represent the prickly leaved portion of a thistle. The part C flares upward and outward from the body B, and has on its surface a series of flutes e. Below the stem, A, the stopper is provided with a shank, h.

What I claim is—

The design for a stopper herein shown and described.

In testimony whereof I affix my signature in presence of two witnesses.

JOHN A. SHEPHARD.
